HEAT EXCHANGE

Edward A. Bertram, Mount Vernon, and David Fulton, Flushing, N. Y., assignors to The Lummus Company, New York, N. Y., a corporation of Delaware

Application March 30, 1942, Serial No. 436,888

6 Claims. (Cl. 261—11)

This invention relates to a fractionation column, bubble tower, vapor absorption device or other type of liquid and gas contact apparatus, and more particularly to an apparatus of this general character wherein hot or cold mediums may be introduced at one or more points into the column for accurately controlling the temperature therein.

An object of the invention is to provide a fractionation column, such as an ammonia-absorption unit with an improved form of heat exchanger for the more accurate temperature control therein.

A further object of the invention is to construct a liquid contact column in such a manner that the plurality of heat exchangers used may be readily inserted into the column or removed therefrom.

A still further object of the invention is to provide an improved form of absorber in which each of the heat exchange units is provided with a fixed top tray having a plurality of perforations therein above the tube bundle for the purpose of collecting descending liquids and distributing them over the tubes of the bundle in heat exchange relation.

While the invention may be used in various types of fractionation or absorption columns, we have shown it in the accompanying drawing as applied to a multiple-deck bubble tower.

In the drawing:

Fig. 1 is a side view of the fractionation tower drawn partly in cross-section and showing the bubble decks and the relation therewith of the heat exchangers.

Fig. 2 is a vertical section through one of the heat exchangers taken on line 2—2 of Fig. 1 looking in the direction of the arrows.

Fig. 3 is a side elevational view of one of the heat exchangers with portions thereof broken away to illustrate the tray support.

Fig. 4 is a top plan view of one of the heat exchangers showing the top tray with its fluid distribution openings and partly broken away to illustrate the location of the plate with respect to the tubes.

Specifically in the drawing, the conventional fractionation tower 10 of suitable diameter and height is provided with a suitable number of horizontal bubble decks 13. The column is provided with the customary inlet and outlet conduits for introducing and discharging vapors and liquids at the top and bottom thereof as will be hereinafter referred to.

Throughout the column and in this instance, 55

preferably below each pair of bubble decks 13, is a horizontal section 15 for supporting a complete heat exchange unit 17. These sections may be of any suitable construction to rigidly support the exchanger units. In the present instance, each of said sections has a pair of diametrically located apertures. Frames 19 and 19a are secured to each section around its respective apertures and form lateral extensions of the tower. Each heat exchange unit 17 is arranged to be demountably secured to one of said frames and to be freely supported by the other frame as a bottom guide. The free end has a floating head cover and thus is free to move with temperature variations.

Referring to Figs. 2, 3 and 4, each heat exchanger unit 17 preferably comprises a plurality of horizontal tubes 23 secured to conventional floating tube sheet 25 on the free end, and a fixed tube sheet 27 on the other. The fixed tube sheet 27 is provided with a manifold or channel 29 having inlet and outlet feed conduits 30 through which hot or cold fluid is circulated through the tube bundle and the free end has a channel 25a.

Baffles 21 and 21a extend between the sides of the column and the heat exchanger guide angles 22. As will be seen in Fig. 2, the upper baffle 21a tends to prevent passage of vapors through the column except through the heat exchange unit, whereas the companion baffle 21 at the lower part of the heat exchange unit serves a complementary purpose. These baffles preferably have a perforation to make them free-draining. The liquid which accumulates on the respective decks is carried downward through the customary downpipes 24 into the usual liquid traps 24a so that there can be no bypassing of the upwardly moving vapors.

Each heat exchange unit is provided with a liquid distributing tray 31, having upstanding side walls 33, such tray being secured to the fixed tube sheet 27 and extending across the top of the tubes in slightly spaced relation thereto to a point adjacent the opposite floating tube sheet 25, from which it is supported by dowels 26.

The liquid from downpipe 24, which overflows the trap chamber 24a, and overruns the tray 31, is thus distributed by the perforations, over the tubes 23.

Each heat exchange unit is also provided with a liquid collecting tray or plate 35 welded to the fixed tube sheet 27 below the tube bundle, such tray being imperforate. This bottom plate 35 has upstanding side walls 37 but is open at the

end 38 adjacent the floating tube sheet 25 from which it is spaced a sufficient distance to permit the free passage of downcoming liquid. Vertical straps or braces 39 are secured to the top tray 31 and the lower tray 35 for supporting the free end of the lower tray.

We have found that a column which is provided with one or more of the removable heat exchanger units as heretofore described, can be accurately controlled as to temperature by directing hot or cold mediums through the heat exchange units and thus in indirect heat exchange with all of the vapors or gases ascending in the column and passing through the heat exchange units in the direction of the arrows. Simultaneously the descending condensate or liquid collected from the superjacent bubble decks distributes itself over the plate and drops through the openings 41 therein and thence distributes over the tubes of the bundle where it is collected on bottom plate 35 and drips from the open free end 38. The liquid flowing from the bottom plate 35 passes down in a thin film to the bubble deck immediately below the particular heat exchanger unit.

We have found particular success in using this equipment as an ammonia absorber, in which air and ammonia are introduced at the point 42 and the water is introduced at 44. The air and unabsorbed ammonia are removed at 46, and the rich aqua is removed at 48. A drain 49 is provided for cleaning out the column from time to time.

As is well known, the production of a predetermined concentration of aqua is a function of the temperature at the absorption stage. Not only is it necessary to have a minimum temperature to avoid boiling off the ammonia, but it is necessary to have a somewhat lower temperature in order to assure the absorption with the minimum amount of water circulation. Furthermore, in ammonia absorption, the average latent heat at 90° F., for example, is approximately 488.5 B. t. u. per pound.

In accordance with our invention, we have found it possible to circulate cooling water through each of the heat exchange units in series beginning with the coldest water at the bottom, and we were able to obtain a high concentration of aqua with the minimum flow of water without requiring external pumps, heat exchangers, etc.

The arrangement for supporting and securing the heat exchange units through the lateral extensions of the tower formed by the frames 19 and 19a has also proved especially satisfactory on this type of unit for it is only necessary to have a relatively small diameter column and yet the heat removed is so great that comparatively large bundles are required with the usual temperature of available cooling water. Such bundles can be projected through the column with portions of the tube bundles extending beyond the actual diameter of the column due to the large spaces provided by the nozzles. The dotted line 10 in Fig. 4 for example, indicates the extent of the column although the effective cross section in the vicinity of the bundles is considerably greater. With such construction there is no objectionable restriction in the vapor space so that the vapor path is not seriously obstructed.

It will be apparent that our invention is applicable to different forms of fractionation or absorption columns in which there are flows of liquid or liquid and vapor streams and that modifications may be made to the precise construction

shown without departing from the invention. Such modifications are thus considered within the scope of our invention.

What we claim is:

1. In a tower for the countercurrent contact of a downflowing liquid and a rising vapor, a bundle of heat exchanger tubing exposed within the tower and disposed horizontally therein, means to circulate temperature-conditioning fluid through said tubing, said bundle being of materially less horizontal width than the internal tower diameter and transversely centered in the tower to provide a pair of vertical vapor passages at opposite sides of the bundle, a foraminous liquid-distributing tray overlying said tube bundle and arranged to receive downflowing liquid and shed a rain of the liquid upon said tubing, a collecting tray underlying the tube bundle to receive said liquid after it has passed through the bundle, a baffle within the tower and disposed at approximately the lower level of the tube bundle and closing the lower end of one of said passages, and a baffle within the tower and disposed at approximately the upper level of the tube bundle and closing the upper end of the other of said vapor passages, said trays and baffles being constructed and arranged to cause vapor ascending within the tower from beneath the tube bundle to flow through the latter crosswise of said rain of liquid.

2. In a tower for the countercurrent contact of a downflowing liquid and a rising vapor, said tower having diametrically located lateral extensions, one of said extensions being closed at its outer end, a removable heat exchanger unit comprising a bundle of horizontal tubing exposed within the tower, means to circulate temperature-conditioning fluid through said tubing, said means including a head at one end of said bundle detachably secured to the other of said extensions and closing the outer end thereof, the bundle extending across the interior of the tower and into both of said extensions for support thereby and being of materially less horizontal width than the internal diameter of the tower to provide a pair of vertical vapor passages at opposite sides of the bundle, a foraminous liquid-distributing tray overlying said tube bundle and arranged to receive downflowing liquid and shed a rain of the liquid upon the tubing, and a collecting tray underlying the tube bundle to receive said liquid after it has passed through the bundle; a baffle fixed within the tower at approximately the lower level of the tube bundle and closing the lower end of one of said passages; and a baffle fixed within the tower at approximately the upper level of the tube bundle and closing the upper end of the other of said passages, said trays and baffles being constructed and arranged to cause vapor ascending within the tower from beneath the tube bundle to flow through the latter crosswise of said rain of liquid, said unit including the tube bundle and trays being removable endwise from the tower after release of said bundle head from the respective tower extension.

3. In a tower for the countercurrent contact of a downflowing liquid and a rising vapor, said tower having diametrically located apertures, frames extending around said apertures and forming lateral extensions of the tower, one of said extensions being closed at its outer end, a removable heat exchanger unit comprising a bundle of horizontal tubing exposed within the tower, means to circulate temperature-conditioning fluid through said tubing, said means including a head at one end of said bundle detachably

secured to the other of said extensions and closing the outer end thereof, the bundle extending across the interior of the tower and into both of said extensions for support thereby and being of a materially less horizontal width than the internal diameter of the tower to provide a pair of vertical vapor passages at opposite sides of the bundle, a foraminous liquid-distributing tray overlying said tube bundle and arranged to receive downflowing liquid and shed a rain of the liquid upon the tubing, and a collecting tray underlying the tube bundle to receive said liquid after it has passed through the bundle; a baffle fixed within the tower at approximately the lower level of the tube bundle and closing the lower end of one of said passages; a baffle fixed within the tower at approximately the upper level of the tube bundle and closing the upper end of the other of said passages, said trays and baffles being constructed and arranged to cause vapor ascending within the tower from beneath the tube bundle to flow through the latter crosswise of said rain of liquid; and track means fixed within the tower and extending between said extensions, said unit including the tube bundle and trays being removable endwise from the tower along said track means after release of said bundle head from the respective tower extension.

4. In a tower for contact of a downflowing liquid and a vapor, a bundle of heat exchanger tubing exposed within the tower and disposed horizontally therein, means to circulate temperature-conditioning fluid through said tubing, a foraminous liquid-distributing tray overlying said tube bundle and arranged to receive downflowing liquid and shed a rain of the liquid upon said tubing, a collecting tray underlying the tube bundle to receive said liquid after it has passed through the bundle, said bundle being of materially less width than the internal diameter of the tower and being transversely centered within the tower to afford spaces at opposite sides of the bundle, and vapor-directing means associated with said opposite sides of the tube bundle, the said trays and the said vapor-directing means being constructed and arranged to constrain the vapor within the tower to flow through the tube bundle crosswise of said rain of liquid.

5. In a tower for contact of a downflowing liquid and a vapor, a heat exchanger unit comprising a bundle of heat exchanger tubing exposed within the tower and disposed horizontally therein, means to circulate temperature-conditioning fluid through said tubing, a foraminous liquid-distributing tray overlying said tube bundle and arranged to receive downflowing liquid and shed a rain of the liquid upon said tubing, and a collecting tray underlying the tube bundle to receive said liquid after it has passed through the bundle, said bundle being of materially less width than the internal diameter of the tower and being transversely centered within the tower to afford spaces at opposite sides of the bundle; means supporting said unit within the tower for horizontal endwise removal therefrom; and vapor-directing means associated with said opposite sides of the tube bundle, the said trays and the said vapor-directing means being constructed and arranged to constrain the vapor within the tower to flow through the tube bundle crosswise of said rain of liquid.
6. A heat exchanger unit for installation in a vapor-liquid contact tower crosswise of the latter and for removal transversely of the tower, comprising a bundle of parallel horizontal tubes, a fixed tube sheet secured to one end of said tubes, a floating tube sheet secured to the opposite end of said tubes, means for circulating a heat exchange medium through the tubes, a foraminous liquid-distributing tray overlying the tube bundle to shed a rain of liquid upon the tubes, an imperforate liquid-collecting tray underlying the tube bundle, both of said trays being secured at one end thereof to one of the tube sheets, a slideable supporting connection between the other tube sheet and the opposite end portion of said foraminous tray to support the latter and permit movement of the floating tube sheet under expansion and contraction of the tubes, and a suspension connection between said opposite end portion of the foraminous tray and the underlying end portion of the imperforate tray for support of the latter.
